UNITED STATES PATENT OFFICE.

HANS A. EGGERSS, OF TOLEDO, OHIO.

BLANK MANUFACTURE AND MACHINE THEREFOR.

Application filed July 25, 1924. Serial No. 728,173.

This invention relates to cutting and scoring sheet material.

This invention has utility when incorporated in connection with sheets of paper, 5 cardboard, corrugated board, fiber stock, etc., especially in handling such as first blanked or in the rough or incomplete pattern form and completing such forms for box blanks by scoring, or by cutting, or slitting, slotting 10 and scoring. The blanks may be progressed in one direction for scoring in said direction, and then progressed in an intersecting direction for additional scoring of the blank in said intersecting direction.

15 In addition to the foregoing objects, this invention relates to the handling of blanks for boxes for performing two different operations thereon in succession, as scoring operations or scoring and cutting operations.

20 Referring to the drawings:

Fig. 1 is a fragmentary plan view of an embodiment of the invention in a machine;

Fig. 2 is a longitudinal sectional view of the feeding mechanism;

25 Fig. 3 is a detail view of the feeding mechanism for the machine of Fig. 1;

Fig. 4 is an end elevation on the line 1V—IV, Fig. 3, of features of the control and drive for the rolls;

30 Fig. 5 is a box blank as a type of product as scored and cut or slotted by the machine as herein disclosed;

Fig. 6 is a side elevation;

Fig. 7 is an elevation of the machine from 35 the opposite side;

Fig. 8 is an end elevation;

Fig. 9 is an enlarged transverse section of that portion of the machine to the rear and at the left in Fig. 8;

40 Fig. 10 is a detail view of features of a stop gage;

Fig. 11 is a section on the line XI—XI, Fig. 1, showing a scoring device;

Fig. 12 is a section on the line XII—XII, 45 Fig. 11;

Fig. 13 is a section on the line XIII—XIII, Fig. 11;

Fig. 14 is a view looking in the direction of the arrow from the line XIV—XIV, 50 Fig. 11;

Fig. 15 is a partial section on the line XV—XV, Fig. 1;

Fig. 16 is a section on the line XVI—XVI, 55 Fig. 15;

Fig. 17 is a diagrammatic view on the line 55 XVII—XVII, Fig. 1;

Fig. 18 is a diagrammatic view similar to Fig. 17, with the ribs and grooves advanced toward each other to grip the sheet stock therebetween; and 60

Fig. 19 is a diagrammatic view of the ribs and grooves of Fig. 18 as completing the scoring operation and progressing in the plane of the stock to avoid stretching thereof. 65

Continuous feed drive.

The object is to get the material into the machine for scoring. The purpose of the feed is to propel the blanks.

Motor 1 is shown having shaft 2 carrying 70 sprocket 3 (Figs. 1, 6, 7,) connected by sprocket chain 4 to sprocket wheel 5 on shaft 6 carried by brackets 7 alongside frame 8. This shaft 6 carries bevel pinion 9 connected through transmission mechanism 10 to drive shaft 11 carried by brackets 12 alongside frame section 13 at an angle to the main frame 8. This shaft 11 carries bevel pinion 14 in mesh with bevel pinion 15 for actuating feed roll 16 carrying gear 17 in mesh with gear 18 on feed roll 19 opposing the roll 16 (Fig. 8). These rolls 16, 19, as well as rolls 16^a, 19^a, similarly continuously driven, receives sheet stock coming from feed table 20. These shafts 6, 11, have therefrom the continuous 80 feed drives. 85

Drive for intermittent devices.

The object is to convert continuous motion into intermittent. The purpose is to operate 90 devices herein intermittently in determined synchronism in sequence.

Mounted on the motor shaft 2 adjacent the sprocket wheel 3, is sprocket wheel 21, having sprocket chain 22 therefrom to drive through variable speed transmission 23. This transmission as controlled by handle 23' determines the speed of shaft 24 extending along the opposite side of the frame 8 from and parallel to the shaft 6. Brackets 25 from the frame 8 mount this shaft 24. Variable speed transmission 26 from this shaft 24 is controlled by lever 27 for determining the relative speed of shaft 28 (Figs. 1, 8) carried by brackets 29, from the frames 8, 13. This shaft 28 is parallel to the shaft 11 and on the opposite side of the frame 13 therefrom. The shaft 28 carries bevel pin- 100 105 110

ion 30 in mesh with bevel pinion 31 on scoring device shaft 32 extending transversely of the frame 13. This shaft 32 carries at its end remote from the pinion 31, a gear 33 in mesh with gear 34 on shaft 35 parallel to the shaft 32 and thereover. These shafts 32, 35, are in bearings 36 mounted by bracket 37 carried by the frame 13.

The machine attendant has as his duty 10 the maintenance of a stack of sheets 42 on the primary feed table 20 to be fed therefrom into primary way of the frame 13.

In the machine herein disclosed this primary supply is directed into the machine with 15 the sheets having their greater dimension extending transversely of the way of frame 13. In box blank manufacture, the longer dimension of the blank ordinarily carries but two score lines 44, 45, (Fig. 5). The position of the blank or sheet 42 to be fed from the table 20 is determined by end or marginal guides 46, 47, while the actual feeding is done by the attendant or operator.

Feed into scoring position.

25 The object is to shift the blanks. The purpose is to so move the blanks that they are in position for receiving scoring action.

The shaft 11 carries bevel pinion 48 in mesh with bevel gear 49 on shaft 50 extending transversely of the frame 13, and mounted in bearings 51 (Figs. 1, 3, 4, 6, 8). These bearings 51 are carried by brackets on the frame spaced away from the feed table 20 and adjacent the movably mounted scoring device of the shafts 32, 35.

40 Mounted integral with each bearing 51 for the shaft 50 is fixed collar or boss 52 having a shorter radius or flat portion 52' cleared by shoe portion 53 of lever 54 having fixed fulcrum 55. Remote from the shoe portion 53, the longer arm of this lever 54 carries roller 56 riding from short radius portion 57 to longer radius portion 58 of cam 45 fixed on the shaft 35. This non-rotary collar or boss 52 at its short radius flat portion 52' provides clearance for this lever 54 in the rocking thereof so that nose 59 as coacting with bearing block 60 may serve to slide such block 60 in ways 60' in the bearing 51 away from the shaft 50 as the shaft 35 brings the cam portion 58 against the roller 56. This means that shaft 61 carrying idle roller 62 opposing live pulling roller 63 on the shaft 50, is thus shifted away from the roller 63 and the sheet 42 may only ride or loosely rest upon this roller 63. However, as the shorter radius cam portion 57 allows the lever 54 so to rock that the roller 62 is against the live 55 roller 63, the sheet material thus engaged receives a pulling action for thrusting into full 60 registering position for scoring as propelled therethrough by the feed rolls 16, 19, or for starting discharge travel therefrom as propelled by the feed rolls 16^a, 19^a.

Stop gage.

70 Follower feed rolls 16^a, 19^a, near the discharge ends of the ways from the frame 8, are mounted in bearing blocks 64, 65, carried by movable brackets 66 resting on the frames 13, 8 (Figs. 1, 9, 10).

The shaft 35 of the scoring device is provided outside of the line of travel of the sheet 42 with cams 67 coacting with bar 67' 75 to depress plungers 68 against the resistance of springs 69. The bar 67' is pivoted to the machine frame remote from the bar 69'. This allows the sheet 42 as being thrust onward to the rolls 16^a, 19^a, to pass over bar 69' between these plungers 68 and ride between sheet engaging arms 70, one at each side of the line of travel of the sheet. These long arms 70 on fulcrum 71 are carried by the brackets 66. Link 72 from the short arm of each lever 70, extends to lever 73 having fulcrum 74. This lever 73 is held toward the block 65 by spring 75. When the sheet stock has passed between the rolls 16^a, 19^a, such levers 70 which has been lifted while the sheet stock was positioned between the rolls 16^a, 19^a, at once drop back to their normal position clear of the bar 69' as the spring 75 expands to be effective through link 72 to rock these levers 70. At once the sheet has 80 passed over the bar 69', the springs 69 snap this bar 69' back to intercepting or stop gage position as directed by the rotation of the cams 67.

Scoring.

90 The object is to define fold lines on the blank material. The purpose is to locate the lines as to position and extent for the desired type of box.

95 As the machine is designed to care for different sizes of box blanks, there is demand for changing the relations between the scoring devices. To this end the scoring devices, carried by the shafts 32, 35, 36^a, 35^a, on the frame are adjustable toward and from each other, and this is quickly accomplished in practice.

100 Along opposite sides of the frame extend racks 76 (Figs. 6, 7, 8, 11, 12) with which mesh pinions 77 in brackets 78 carrying bearing blocks 79 for shafts 32^a, 35^a, similar to the mounting for the brackets 37, 66. A ratchet type socket wrench at each squared end 80 of shaft 81 carrying the pinions 77 may insure 105 parallel travel in adjusting the brackets 78 to the position desired as to the frame. When so adjusted, clamps 81' anchor such brackets 78 against shifting. These shafts 32^a, 35^a are actuated by gears 30, 31, from the 110 shaft 24.

115 On the shaft 32^a is intermediate collar 82 and terminal collars 83. Outside the collars 83 are eccentric terminal trunnions or bearings 120 fixed with the shaft 32^a. These collars 82, 83, 125 130

are connected by groove bar or channel 85 (Figs. 11, 13).

On the shaft 35^a is intermediate collars 82, and terminal collars 83 outside of which are 5 eccentric trunnions or bearings 84 fixed with the shaft 35^a. These collars 82, 83, are connected by rib or plunger 86 as a tongue movable toward, into and with the groove bar 85.

The collars 83 on the shaft 32^a have fixed 10 therewith strips 87 to slide in guide way 88 of the adjacent collars 83 on the shaft 35^a. Dovetailed ways 89 in the collars 83 are held in alignment by guide 90 fixed with the upper collar 83. Accordingly, in the rotation of the 15 shafts 32^a, 35^a, simultaneously toward each other as to these collars 82, 83, there is first a shifting of the groove bar 85 up against the under side of the sheet 42 to be scored, while the opposing plunger or ribbed bar 86 has its 20 tongue come down into gripping relation with the sheet from the opposite side thereof and in position to register with such groove. During this operation movement of the scoring 25 effecting members into stock gripping position, there is sliding of the strips 87 as to the collars 83 on the shaft 35^a, and there is sliding of the guide 90 as to the dovetailed grooves or ways 89 in the collars 83 on the shaft 32^a. The further rotation of the shafts 30 32^a, 35^a, mounted in eccentric bearings 84 thrusts the tongue 86 into the groove 85, and in this operation these scoring effecting members 85, 86, held against relative rotation, travel in a direction transversely to that of 35 their gripping action, and in the direction of travel of the sheet of stock.

This is a feature of material importance involving one scoring means, acting upon the same sheet of stock simultaneously with another independent scoring means, for there 40 is first a gripping of the stock at the desired register position, for uniformity in starting. While slight differences in stock might create departures were the stock thereafter subjected to stretching, herein the further action 45 of scoring tends more to crowd, slacken or bulge the stock between the scoring devices, thus avoiding any tendency to weakening or unevenness or other irregularities which 50 might detract from the production of a uniform superior product.

Transfer table.

55 The object of the transfer table is to provide a station between the different directions of blank travel. The purpose of the transfer table is to maintain a reserve for the maintenance of feed supply for the second scoring 60 device.

As the scorings 44, 45, are simultaneously effected, with the pair of these first scoring means set to crowd toward each other, the clearing of the stock by such means, times 65 the clearing of the stop gage, and the rolls

16^a, 19^a, thrust this sheet of stock from the frame, to transfer table 91, which is equipped to receive a stack of sheets, and have such fed therefrom, by being pulled off the bottom. 70

Feed from transfer table.

The object is to remove the blanks from the table. The purpose is so to move the blanks separately that they are in position for 75 receiving scoring action.

Continuously driven from the shaft 6 by transmission mechanism 32' is eccentric 36' coacting through connecting rod 37' and slide 38 (Fig. 2) in way 39 of the feed table 91 to 80 reciprocate upwardly projecting fingers 41, and thereby pull a lower sheet 42 off a stack of sheets of partially formed blanks on this table 91. This action of the fingers 41 is to urge the lowermost sheet from such stack 85 along the upper side of this table 91 to have the forward edge of such sheet enter between the constantly rotating first feed rolls 16^b, 19^b. A guard 43, holds back the upper sheets 90 of such stack and allows but the bottom sheet to be shifted from such table into the machine in the timed sequence as determined by this feed.

Second scoring.

The object is to further create weakening lines in the stock. The purpose is to locate these additional weakening lines in a direction at an angle to the direction of the first scoring. 100

This sheet material delivered from the transfer table (Fig. 1) is now with its shorter dimension extending transversely of the frame 8. Bar 69' determines the stopping position of the sheet along this second way of 105 the frame 8. This first stop after leaving the transfer table or intermediate receiver 91, places such sheet in position to have transverse scorings 92, 93, 94, 95. The eccentrics 32^a, 35^a, in the stock gripping position move, at 110 the stock, toward the oppositely rotating pair of eccentrics 32^a, 35^a, and thus shorten the total distance for the stock extent therebetween as to the pair of scorings. Additional scoring means may also be so disposed to act 115 on the stock as shown in Fig. 17.

These scorings 92, 93, 94, 95, are along the stock for a greater distance than the first scorings. The feed rolls operate on the way of the frame 13 for quick travel of the stock 120 away from scoring operations. It is in order to have such speed of travel even greater along the way of the frame 8 than along the frame 13. To this end, drive gears 14^a (Fig. 6) on the shaft 6 may be of less diameter than the intermeshing driven gears to insure the higher speed rotation of continuously running feed rolls 16^a, 19^a. Similarly gears 14^a on the shaft 6 insure higher speed of operation of other feed or pulling rolls 16^a, 19^a. 125 130

The multiple simultaneous scoring herein is a distortion or stretching of the stock local to and in the tongue and groove registry regions only. No disturbance of the stock between these scoring offsets occurs for the stock between the scoring devices is not only not placed under tension, but in fact is slackened up. This is effected by having the eccentrics, as gripping the stock, work toward each other 5 in completing the scoring. The degree of eccentricity may be greater for scoring devices beyond the inner opposing pair to insure release against tension on the stock at all regions. This traveling of the gripped 10 stock during completion of the multiple scorings is an important factor in the production of a uniform superior product even from coarse stock. It is to be noted the entrance of the rib into the groove is a straight pressing action of uniform squeezing nature through the tongue and groove coacting with the stock.

Slotting.

25 The object is to cut through the blanks. The purpose is to sever adjacent portions of the blank so that in box setting up, they may be relatively moved.

After this second scoring operation, the 30 stop 69' at the rolls 16', 19^a, releases the sheet to pass further along the way of this frame 8 to a second similar stop, thereby bringing the sheet 42 into registering position for the slotting operation.

35 The shaft 24 carries pinions 97 in mesh with pinions 98 (Figs. 1, 7) on shafts 102 extending transversely of the frame 8, similarly to the shafts 32^a for the various scoring devices. These shafts 102, are mounted in 40 brackets 78^a, and the pinions 97 are adjustable along the shaft 24, as are the driving connections and mountings for the adjustable scoring means.

On this second way of the frame, the fixed 45 scoring means is toward the table 91, thus permitting the remaining adjustable elements, even including the stops 69' to be adjusted theretoward, and thus take advantage of any shortening up of the stock in the handling of smaller blanks. This is a material factor in maximum production rate.

The shaft 102 (Figs. 15, 16) is provided 50 with collars 103 having radial cams or grooves 104. The collars 103 are eccentric 55 and coact with rollers 105 for effecting the downward or cutting thrust of blade 106 guided by ways 107 of frame 108 fixed with the bracket 78^a. Rollers 109 from the blade 106 serve to lift the blade away from opposing members 110. The operation of the 60 blades 106 toward the opposing members 110, effects the slotting or cutting of lines 111 (Fig. 5), as extensions from the scorings 92, 93, 94, in the box blank 42, thereby completing such blank. The frame 108 may be ad-

justed as to the bracket 78^a by rotation of screw 108' fixed with the bracket 78^a and having threaded connection with the frame 108.

Extending transversely of the frames 8, 13, 70 over the roll pairs are frame members 112 connecting the brackets 78, 78^a for giving more rigidity to the brackets as carrying the rolls.

Finished blank discharge.

75

The object is to move the blanks from the machine. The purpose is to have the scored blanks taken away from the scoring devices so that additional blanks may be there acted upon.

80

The shaft 6 extending from the frame 8 away from the frame 13, carries pinion 113 in mesh with pinion 114 (Figs. 1, 6), for driving shaft 115 carrying conveyor belt 116 to effect removal of the finished box blanks from the machine. This conveyor passes about follower roll 117 adjacent the discharge end of the frame 8. The blanks as thus removed from the machine are deposited on final delivery table 118, which may be mounted on wheels 119, and thus be a truck for transferring the blanks as completed to any desired location in the plant, or for packing and shipping. This removal of the 90 blanks by the conveyor is generally used only where shorter stock is being handled and table 120 connected to terminal brackets 66 of the terminal feed roll pair is adjusted along the frame 8 away from the motor 2. This 95 table 120 then completes the way on the frame 8 from such final feed roll pair to effect delivery to the belt 116.

100

The disclosure herein is one which may be quickly set for changing the character of output. It may have its production rate built up to a maximum at all times. It insures accurate scoring, even of corrugated stock.

105

As suggested, the speed of travel of the sheet 42 along the way of the frame 8 is at a greater lineal rate than the speed of travel of the sheet 42 along the way of the frame 13 which delivers to the intermediate transfer table 91.

110

However, as the way on the frame 13 is materially shorter as to the length of the stock to be cared for, the feed rate per sheet may be such as to bring about an accumulation of stock on the transfer or intermediate table 91. There is a factor of utility in this mode of operation in that the attendant or operator of the machine supplying stacks or sheets on the primary feed table 20 and manually feeding therefrom, may replenish these 115 stacks on the primary feed table with possibly one or two idle operations on the scoring means on the way of the frame 13. However, the reserve on the intermediate table 91 insures that there is no idle operation of 120 125 130

the means along the way of the frame 8. This factor of mechanism output has value in the general machine operation for maintained maximum output.

5. What is claimed and it is desired to secure by Letters Patent is:

1. A machine embodying a first way portion for receiving stock with the longer dimension of the stock transversely thereof, 10 first scoring means transversely of the first way portion for effecting longitudinal scoring of said stock, a second way portion at an angle to the first way portion for receiving stock with the shorter dimension of the stock 15 transversely thereof, second scoring means transversely of the second way portion, a receiver between said way portions for stock accumulation from the first way portion, and a feeder for removing the bottom sheet from 20 said receiver and delivering to the said second way portion.

2. A machine embodying a first way portion for receiving stock, first scoring means transversely thereof, a second way portion 25 for receiving stock from the first way, second scoring means transversely of the second way portion, and driving means for shifting the stock from said scoring means, said driving means coacting at different speeds in the 30 different way portions, whereby the longer dimension of stock for scoring may be in the lesser portion of said way.

3. A machine embodying a first way portion for receiving stock, first scoring means 35 transversely thereof, a second way portion for receiving stock from the first way portion, and second scoring means transversely of the second way portion and disposed for greater lineal extent along said second way portion 40 than the first scoring means along said first way portion, and driving means at one linear speed for stock along said first way portion and at a greater linear speed along said second way portion.

45. 4. A machine embodying a way, a first scoring means for one direction of material on said way, a second scoring means beyond said first scoring means, said second scoring means coacting for another direction of scoring of the material, driving means for progressing the material from the first scoring means to the second scoring means, these scoring means embodying a plunger and a seat, said plunger being shiftable to crowd 50 material into said seat and actuating means for the plunger and seat to shift in a common direction together.

5. A scoring device for sheet material embodying a plunger and a seat, said plunger 60 being shiftable relatively to the seat to crowd sheet material into said seat, and an actuating means for moving the plunger toward and from the seat and also moving the plunger in the direction of travel of the sheet material.

6. A scoring device embodying a pair of parallel members determining a scoring plane therebetween, eccentrics on opposite sides of said plane for carrying said members, and guiding means extending between the members transversely of said plane for holding the members from relative rotation. 70

7. A scoring device embodying a pair of members coacting for determining a scoring plane therebetween, eccentrics carrying said 75 members, driving means oppositely rotating the eccentrics for shifting the members relatively toward each other, and guiding coacting means between the members extending transversely of said plane for holding the 80 members for simultaneous movement transversely of their movement toward each other.

8. A scoring device embodying a grooved member, an opposing ribbed member, oppositely rotatable actuating means for shifting 85 the members to bring the rib into said groove, and guiding means coacting between the members for holding the members to shift transversely of their movement toward each other.

9. The method of acting upon sheet material by an opposing plunger and seat on opposite sides of the supported and stationary material, embodying effecting relative movement between said plunger and seat to reduce the spacing distance therebetween determined 90 by the material, and during said movement shifting from a first position of rest said material together with the plunger and seat in a common direction in the plane of the material to a second position of rest. 95

10. The method of scoring sheet material by causing a pair of scoring effecting members to grip the material, and during said gripping to shift one of said members toward the other in the direction of the extent of 100 said material.

11. A scoring device for sheet material embodying a plunger having a projecting tongue and a seat providing a groove for receiving said tongue, said plunger being shiftable relatively to the sheet to crowd sheet material into said seat, and an actuating means for moving the plunger toward and from the seat and also moving the plunger in the direction of travel of the sheet material. 110

12. The method of effecting a plurality of parallel scorings in sheet material comprising causing a pair of scoring members to approach each other in material gripping coaction, and then during their further movement into scoring effecting position causing said pair of members to shift to reduce the distance between such pair and an adjacent pair of scoring members, thereby relieving the sheet material of strain therebetween. 115

13. The combination of a pair of parallel scoring devices on opposite sides of the plane of a sheet of material to be scored and driving means for operating said devices simultaneously on the sheet material. 120

14. The combination of a pair of parallel scoring devices, and driving means for operating said devices simultaneously on the sheet material, there being control means for said devices effecting first gripping of the material and then shifting of the devices engaging the material toward each other.

15. A sheet material scoring machine embodying a way for the material, a pair of scoring devices mounted transversely of such

way, each device comprising a pair of sheet material engaged members, mounting means for shifting the members in the direction of said way, driving means for the devices to effect simultaneous gripping of the material by the two devices and then shifting of said members as carried by said mounting means toward each other.

In witness whereof I affix my signature.

HANS A. EGGERSS.
